Specification of Letters Patent.

Patented Feb. 3, 1920.

Application filed September 23, 1919. Serial No. 325,659

To all whom it may concern:

Be it known that I, JOHN J. FLEMING, a citizen of the United States, residing at Cambridge, in the county of Middlesex and 5 State of Massachusetts, have invented new and useful Improvements in Cigarette-Pack-
ages, of which the following is a specifica-
tion.

This invention has for its object to pro-
vide a cigarette package including a bunch 10 of cigarettes, contacting with each other throughout the bunch, and a wrapper or casing therefor, closely confining the bunch, the arrangement being such that when the 15 casing is opened at one end, the user is enabled to grasp some of the cigarettes between his thumb and finger and withdraw the same more conveniently than heretofore and without liability of injury to the cigar-
ettes, until the bunch is so loosened that 20 the remaining cigarettes may be conveniently grasped and withdrawn.

I accomplish this result by inserting in the inner end of the casing, or the end op-
posite the end which is opened, to permit 25 the withdrawal of the cigarettes, a position-
ing device, which supports the ends of some 30 of the cigarettes offset endwise outwardly from the ends of others, the bunch present-
ing at the opened outer end of the casing, a 35 key row of cigarettes, the outer end portions of the members of which project sufficiently from the adjoining rows to enable them to be conveniently grasped between the 40 user's thumb and finger, and withdrawn, until the bunch is sufficiently loosened to permit any of the remaining cigarettes to be conveniently grasped and withdrawn.

Of the accompanying drawing forming a part of this specification,

Figure 1 is a side view of a cigarette pack-
age embodying the invention shown partly 45 in section.

Fig. 2 is a perspective view of the posi-
tioning device shown in section by Fig. 1.

The same reference characters indicate the same parts in all the figures.

In the drawings 12 represents a wrapper 50 containing a bunch of cigarettes 13, ar-
ranged in rows, the cigarettes being bunched and the wrapper applied in the usual or

any suitable way, the wrapper entirely in-
closing the bunch.

In carrying out the invention, I insert in the wrapper, in contact with the inner end 55 thereof, a false bottom formed to support cigarettes in a different plane from the ends of the others, so that, when the package is opened at its outer end the end which is uppermost in the drawing, the upper ends 60 of alternate rows of cigarettes project from the upper ends of the other rows as indicated by dotted lines, the projecting ends being exposed at opposite sides, and thus adapted to be conveniently grasped between 65 a thumb and finger for removal. When the projecting cigarettes have been removed the others are loose in the wrapper so that they may be removed without difficulty.

The false bottom 14 may be of corrugated 70 sheet material such as paper, the corruga-
tions presenting alternating depressed and raised portions adapted to support the ends of some of the cigarettes in a different plane from the ends of the others.

The false bottom and the cigarettes may 75 be assembled before the casing is applied, and then inclosed by the casing.

A cigarette package embodying the in-
vention does not require any change in, or 80 modification of the wrapper, or inclosing
portion, other than to slightly increase the
length or distance between the inner and
outer ends. The false bottom 13 does not
appreciably add to the expense of the 85
package.

In pointing out the invention by the ap-
pended claim, I call the rows whose outer 90 ends are nearest the outer end of the casing,
the higher rows, and the others the lower
rows. As shown by the drawing, the rows
forming two opposite sides of the bunch,
are higher rows, so that these and the inter-
mediate higher rows collectively form an
extended support on which the outer end of 95
the casing lies flat.

I claim:

A cigarette package comprising a casing 100 adapted to be opened at its outer end, and a bunch of cigarettes arranged in rows and confined by the casing in close contact with each other throughout the bunch, the

casing being provided at its inner end with means supporting alternate rows higher than the other rows, the higher rows forming an extended support for the outer end of the casing, said higher rows being spaced apart so that when the casing is opened, the members of a higher row may be grasped by

a thumb and finger and withdrawn from the bunch, the withdrawal of said row loosening the bunch and facilitating the removal 10 of the remaining cigarettes.

In testimony whereof I have affixed my signature.

JOHN J. FLEMING.
